UNITED STATES PATENT OFFICE

FREDERICK E. MANN, OF CHERRYDALE, VIRGINIA

RECEPTACLE SUPPORT

Application filed March 23, 1929. Serial No. 349,486.

The present invention appertains to new and useful improvements in supports, and more particularly to a support for small receptacles such as tobacco cans and the like.

5 The principal object of the invention is to provide a support of this character which can be built into the receptacle without in any respect interfering with the removal of the contents thereof.

10 Another important object of the invention is to provide means for small receptacles, capable of being used when the occasion arises, to support the receptacle without difficult preparation.

15 Still another object of importance is to provide an attachment for small receptacles which because of its extremely brief construction will not materially increase the cost of production.

20 These and other objects of the invention will become more apparent as the description of the invention is better understood.

In the drawings:—

Figure 1 represents a fragmentary vertical 25 sectional view showing a receptacle with its lid opened and with the present invention disclosed therein.

Fig. 2 represents a vertical sectional view taken substantially on the line 2—2 of Fig. 1.

30 Fig. 3 represents a vertical sectional view of the receptacle, showing its lid closed and also showing the device disposed in a somewhat modified manner.

Fig. 4 represents a vertical sectional view 35 taken substantially on the line 4—4 of Fig. 3, but showing the member broken and disposed outwardly of the receptacle to provide supporting hooks.

Fig. 5 is a perspective view of the receptacle attachment intact.

Referring to the drawings wherein like numerals designate like parts, Figs. 1 to 4 inclusive each show a receptacle 3 of the usual type in which pipe tobacco is sold. This type 45 of receptacle is provided with a lid 4 hingedly connected to the receptacle 3 by a pin 5 extending through complementary hinge constructions 6 on the receptacle, and lid. This species of tobacco can also has a shoulder 7 formed by a bulge extending substantially

around the perimeter of the can adjacent the upper edge.

The formation of the shoulder 7 incidentally provides a groove 8 at the inner side of the receptacle which accommodates the form 55 of the invention as shown in Fig. 3. The supporting attachment shown in Fig. 5 embodies the present invention and may be disposed in association with the receptacle in either the manner shown in Fig. 1 or in Fig. 3. In Fig. 60 1, the attachment is disposed within the lid 4, while in Fig. 3, the same is sprung into the groove 8 and in either manner, the device does not interfere with the filling or removal of tobacco.

65 The novel attachment consists of an elongated strand of relatively stiff yet ductile material and this attachment is generally referred to by numeral 9. The strand is bent adjacent its ends at the points 10—10, inwardly in spaced parallelism to its intermediate portion. The end portions of the strand are bent laterally as at 11 and backwardly as at 12 in a manner so that they may be easily clinched around the hinge pin 5 in the manner 70 shown in Figs. 1 to 4 inclusive.

75 The intermediate portion of the strand is notched as at 13 so that the same may be parted without difficulty to form the hook members whereby the can may be supported 80 in the manner shown in Fig. 4.

As is shown in Fig. 1 the strand is normally disposed within the lid and need not be disturbed until the occasion arises for supporting the can. The strand may be gripped at 85 opposite sides of the notch 13 and by bending the strand at this point, the same will part the sections of the strand, and may then be bent outwardly from the lid 4 and the lid closed in the manner shown in Fig. 4, while the receptacle is maintained in the supported position shown.

Instead of being disposed within the lid, Fig. 3, shows the attachment sprung into the groove 8. The strand may be easily disengaged from the groove 8 and broken in the manner heretofore described, and bent outwardly to provide the supporting hook in the same manner.

Obviously certain changes in the specific 100

shape, size, and materials may be resorted to without departing from the spirit and scope of the invention as claimed hereinafter.

Having thus described my invention, what I claim as new is:—

5   1. A hanger for receptacles comprising an elongated member, the end portions of said member being connected to said receptacle, the intermediate portions of said member being weakened so that the member may be broken, and bent outwardly to provide supporting hooks for the receptacle.

10   2. A hanger for receptacles comprising an elongated member, the end portions of the said member being connected to said receptacle, the intermediate portion of the member being provided with a notch to weaken the member so that the same may be broken and bent to provide a pair of supporting hooks for the receptacle.

15   20   In testimony whereof I affix my signature.
FREDERICK E. MANN.
